UNITED STATES PATENT OFFICE.

ARTHUR RONALD TRIST, OF LONDON, ENGLAND.

GOVERNING DEVICE FOR AUTOMATICALLY CONTROLLING THE SUPPLY OF FEED-WATER TO STEAM-BOILERS AND FOR LIKE PURPOSES.

1,251,843.

Specification of Letters Patent.

Patented Jan. 1, 1918.

Application filed June 12, 1914. Serial No. 844,755.

To all whom it may concern:

Be it known that I, ARTHUR RONALD TRIST, subject of the King of Great Britain and Ireland, residing at 4 Lloyd's avenue, 5 in the city of London, England, have invented new and useful Improvements in and Relating to Governing Devices for Automatically Controlling the Supply of Feed-Water to Steam-Boilers and for like Purposes, of which the following is a specification.

This invention relates to governing devices for automatically controlling the supply of fluid under pressure and is particularly applicable to the supply of feed water to steam boilers under conditions in which the pressure of the fluid being supplied is utilized as the agent by which the power of the fluid pressure creating device is regulated according to the demand made on the supply of fluid under pressure.

In known methods for effecting this purpose the objectionable feature of "hunting" has obtained and this invention has for its 25 object the complete automatic control without any risk of "hunting" taking place and such control can be effectively arranged within a very small range of pressure.

The invention consists in the construction of a pressure controlled device provided with means by which the said controlling device is held in check for small variations in pressure, so that it does not immediately respond thereto, and is thus 35 prevented from any "hunting" effect on the device controlled.

In order that the invention may be the better understood, I will now proceed to describe the same in relation to the accompanying drawings, reference being had to the letters and figures marked thereon. Like letters refer to like parts in the various figures in which:—

Figure 1 shows the general arrangement 45 of apparatus for feeding a battery of boilers from one feed pump with my invention applied thereto, only one boiler of the battery being indicated.

Fig. 2 is a sectional view with parts shown 50 in elevation of an apparatus constructed in accordance with my invention.

Fig. 2^a is a similar view to Fig. 2, but showing the parts in different positions.

Fig. 3 is a part side elevation showing 55 the detent gear.

Fig. 4 is a detail view showing the valves and their associated parts on an enlarged scale.

To show how the invention can be carried into effect, I will describe it in relation 60 to a steam pump *a* feeding a battery of boilers of which one boiler *b* is shown, the pump being controlled by the pressure in the feed main *c* as to the rate of its operation. To the feed main *c* between the pump *a* and 65 the boiler *b* is connected a power device *d* having a piston *e* or the like adapted to operate against an adjustable yielding resistance such as a spring *f* acting in opposition to the feed water pressure so that as the 70 pressure in the feed main *c* rises, the piston *e* moves against the yielding resistance of the spring *f* and the piston rod *g* is adapted to contact with a stem *s* which carries at its lower part valves *h*¹ and *h*². These valves 75 *h*¹ and *h*² are disposed each side of and adapted to co-act with a valve-seat member *h* and control the valve *i* of the steam supply pipe *k* to the pump *a* through the medium of the power device *l*. I prefer to 80 arrange the valve *i* to be operated by a power device *l* comprising a piston and cylinder similar to that hereinbefore described and also fitted with some form of yielding resistance such as springs *m* which 85 will return the power device *l* to its initial position when the operating pressure is cut off therefrom consequent upon the control valves *h*¹ and *h*² being operated by the power device *d* under the action of the pressure of the feed main *c*. After the power 90 device *d* has been operated the control valves *h*¹ and *h*² are kept in such a position 95 so as to maintain the supply of steam from the pipe *k* to the power device *l* of the valve *i* by means of a detent *n* pivoted at *o* on the frame and spring pressed by spring *p*, the nose *q* of the detent *n* automatically engaging with an abutment *r* carried by the stem *s* of the control valves *h*¹ and *h*². Upon 100 the piston rod *g* of the power device *d* I arrange a cross head *t* carrying a rolling surface *u* on each side adapted to co-act with rollers *v* pivoted on the detent *n* so that on the outward stroke of the power 105 device *d*, the surfaces *u* recede from the rollers *v* and allow the nose *q* to engage with the abutment *r* of the control valves *h*¹ and *h*² in such a way that when the pressure in the feed main *c* drops the roller 110

v on the cross head t gradually withdraws the nose q of the detent n from co-action with the abutment r thus releasing the control valves h¹ and h² which under suitable pressure such as from springs w moves so as to close the valve h² to the passage of main steam to the power device l and open the valve h¹ to the exhaust x so that the valve i opens and steam is again admitted to the pump a. In order that the apparatus can be worked through very narrow limits, the cross head t is adapted to be adjustable on the piston rod g and the abutment r is adjustably fixed on the stem s. 10
15 By this arrangement, it is possible not only to adjust in the simplest manner the critical terminal pressure which will operate the control valves h¹ and h² to the pressure which will operate the power device l of the valve i but also to regulate the drop in pressure that it is found in practice to be desirable to allow as a suitable range within which the valve i should be moved from the "all open" position to the "completely closed" position. 20
25

To prevent damage to the valve h¹ the stem s carries at its upper end a plunger s¹ which is adapted to slide axially therein, and the end of said plunger s¹ bears against one end 30 of a spring s² located in a recess in the stem s in order to prevent the heavy force from the piston e from being directly and wholly transmitted to the valve h¹, the only force transmitted being limited to that exerted 35 by the spring s² as the range of such spring is not exhausted when the crosshead t reaches its lower terminal position.

It will be understood that in Fig. 1 I have shown a power operated feed check valve y 40 controlled by a float device z as part of the usual equipment of a battery of boilers which has been put in to complete the automatic features of the arrangement described.

I may reverse the action of the valves h¹ and h² by making the passage communicating with the pipe x the steam supply, and the passage communicating with the pipe k the exhaust outlet, in order to effect the particular purpose in view which may be under 45 different circumstances to those of which the device shown in the drawing works 50 under.

Having thus fully described my invention, I claim as new and desire to secure by Letters Patent:—

1. A governing device for automatically controlling the supply of fluids by the pressure of supply comprising in combination, a power device in connection with the supply

pressure, a yielding resistance adapted to 60 operate in opposition to said power device, a fluid operated control device controlling the operation of the supplying device of fluid under pressure adapted to co-act with said power device, an automatic positively locking retaining device for maintaining the said control device closed adapted to become operative only when the maximum motion of the power device has taken place against the maximum effort of the yielding resistance 65 and a releasing device carried by the movable part of the power device adapted to withdraw the said retaining device from its locking co-action with the control device when a given variation of pressure of the 70 fluid under supply has been attained, substantially as described.

2. A governing device for automatically controlling the supply of fluids by the pressure of supply comprising in combination 80 a cylinder in connection with the supply pressure, a piston in said cylinder, a spring adapted to act on said piston against the supply pressure, a fluid supply device, a control device, controlling the supply of 85 energy to the fluid supply device, an independent retaining device adapted to positively lock the control device in its inoperative position after maximum motion of the said piston and a releasing device carried 90 by the piston or its rod adapted to withdraw the positive lock of the retaining device on a given variation of pressure of supply, substantially as described.

3. A governing device for automatically 95 controlling the supply of fluids by the pressure of supply comprising in combination a power device in connection with the supply pressure, a relay control device operated by the said pressure adapted to control external energy, a second power device operated by said external energy, a control device operated by said second power device for controlling the energy transmitted to the fluid supplying device and an automatic 100 positively locking retaining device for maintaining the relay control device in the position for admitting fluid pressure to the said second power device in order to cut off the energy to the said fluid supplying device, 110 substantially as described.

In testimony whereof I have signed my name to this specification in the presence of two subscribing witnesses.

ARTHUR RONALD TRIST.
